UNITED STATES PATENT OFFICE.

JESSE F. RILEY AND BLAIR S. FOCKLER, OF HAGERSTOWN, MARYLAND.

BRAKE-HANGER.

1,400,986.

Specification of Letters Patent. Patented Dec. 20, 1921.

Application filed December 6, 1920. Serial No. 428,719.

To all whom it may concern:

Be it known that we, JESSE F. RILEY and BLAIR S. FOCKLER, citizens of the United States, residing at Hagerstown, in the county of Washington and State of Maryland, have invented new and useful Improvements in Brake-Hangers, of which the following is a specification.

This invention relates to brake hanger for locomotives, and has for its primary object the provision of a hanger of this character designed to convey sand from a suitable source to the track, and to also accommodate one or more air lines through the instrumentality of which the passage for the sand may be made free from all obstructions.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a fragmentary view of a locomotive showing the hanger in operative position.

Fig. 2 is an edge elevation of the hanger.

Fig. 3 is an enlarged side elevation of the hanger, partly in section.

Fig. 4 is a transverse sectional view taken on line 4—4 of Fig. 3.

Fig. 5 is a sectional view taken on line 5—5 of Fig. 3.

Referring to the drawings in detail A indicates generally the hanger, formed at its upper end to provide a bearing 10. The opposite end of the hanger is relatively wide and slightly offset from the main body portion of the hanger as at 11. The hanger embodies a relatively thin portion 12, and a relatively thick portion 13, both extending longitudinally of the hanger as shown. Projecting from the opposed longitudinal edges of the hanger adjacent its upper end are sleeve-like portions 14, which are internally threaded as at 15, to accommodate conduit 16, leading from a suitable sand supply. The sleeves 15 open into a longitudinally disposed bore 17, extending throughout the major part of the length of the hanger, and opening at the lower wide extremity 11 thereof.

Manifestly the sand from its source of supply is conveyed through the conduit 17 and sleeve 14 into the bore 17, passing through the latter to the tracks, the construction being such as to eliminate the trouble and expense incident to the tearing or breaking away of sand pipes which are usually held in operative position by means of clamps. Each sleeve 14 is provided with a threaded opening 18 to accommodate an air pipe or line 19, so that should the bore 17 become clogged or otherwise obstructed by sand or other formed matter, it could be readily opened by admitting air from a suitable source through the openings 18 into the bore 17.

While it is believed that from the foregoing description the nature and advantages of the invention will be readily apparent, we desire to have it known that we do not limit ourselves to what is herein shown and described, and that such changes may be resorted to when desired as fall within the scope of what is claimed.

What we claim is:

1. A hanger of the character described having a longitudinally disposed bore opening at the lower end of the hanger, and adapted to convey sand through the hanger, said bore opening at one side of the hanger adjacent its upper end, and means for securing a sand supply pipe to the hanger at the inlet opening of the bore.

2. A hanger of the character described including a body portion and a relatively wide lower extremity, said body portion having a longitudinally disposed bore opening at the bottom thereof, and at one side adjacent the upper end thereof, and means for connecting a sand supply pipe to the hanger at the inlet end of said bore.

3. A hanger of the character described having a longitudinally disposed bore opening at the bottom of the hanger and at the opposite sides thereof adjacent the upper end of the hanger, and means carried by the hanger for coupling the adjacent end of sand supply pipes thereto at the inlet openings of said bore.

4. A hanger of the character described having a longitudinally disposed bore opening at the lower end of the hanger and at one side adjacent the upper end thereof, means carried by the hanger for coupling a sand supply pipe thereto at the inlet opening of the bore, and said hanger having an air

inlet opening communicating with the bore for the purpose specified.

5. A hanger of the character described having a longitudinally disposed bore opening at one end of the hanger and at the opposite sides thereof adjacent its upper end, sleeves projecting from the sides of the hanger in line with said openings, said

sleeves being threaded and having air inlet openings communicating with said bore for the purpose specified.

In testimony whereof we affix our signatures.

JESSE F. RILEY.
BLAIR S. FOCKLER.
